CLAIM

The ornamental design for an olive infuser, as shown and described.

DESCRIPTION

FIG. 1 is a perspective view of an olive infuser showing our new design.

FIG. 2 is a front view thereof.

FIG. 3 is a rear view thereof.

FIG. 4 is a top plan view thereof; and,

FIG. 5 is a bottom plan view thereof.

The broken lines are for illustrative purposes only and form no part of the claimed design.
